Primary Examiner — Marie D. Fast Horse(74) *Attorney, Agent, or Firm* — Leason Ellis LLP(57) **CLAIM**

The ornamental design for an electronic touch board, as shown and described.

DESCRIPTION

FIG. 1 is a perspective view of an electronic touch board according to our new design;

FIG. 2 is another perspective view thereof;

FIG. 3 is a right, side view thereof;

FIG. 4 is a left, side view thereof;

FIG. 5 is a front view thereof;

FIG. 6 is a rear view thereof;

FIG. 7 is a top plan view thereof; and,

FIG. 8 is a bottom plan view thereof.

The broken-line showing of a portion of a device is included for the purpose of illustrating environmental structure and form no part of the claimed design.

1 Claim, 8 Drawing Sheets(56)
